SHOE DAUBER

Linzy W. Brooks, Portland, Oreg., assignor of
one-third to Howard P. Arnest, Portland,
Oreg.

Application June 20, 1932. Serial No. 618,363

4 Claims. (Cl. 15—135)

My present invention relates generally to daubers used for applying paste to shoes in the shining thereof, and is more particularly designed for the practical use of a paste supply in a collapsible tube, which may be replaced when collapsed, and from which the supply of paste may be used as needed without exposing the unused paste, and without soiling the hands.

As ordinarily used from a box, the supply of paste is exposed to the drying influence of the air and, to offset rapid deterioration, is usually packed with a grease which prevents such rapid drying, but at the same time impairs the efficiency of the paste. It is my primary object to provide a dauber receiving its supply of paste from a collapsible paste tube or fountain, where the supply is at all times protected, and wherein a pure, highly efficient paste may be employed without grease or other adulterations.

Obviously such a dauber as proposed by my invention must, for practical purposes, be made to employ only a tube formed expressly for such dauber, and must have some means for protecting the bristles and the paste remaining therein after each operation, from drying and hardening. Hence it is a further object to provide a dauber in connection with which the arrangements are such as to compel the use of a specially prepared collapsible tube, and a further object is the provision of a protecting cap which may be easily and quickly applied to cover the bristles during periods of disuse, without soiling the hands, and without bending or breaking the bristles.

With these and other objects in mind, as will plainly appear in the course of the following specification, my invention resides in the shoe dauber which I will now describe in detail in connection with the accompanying drawing, which forms a part of this specification, and in which,

Figure 1 is a side elevation of my improved shoe dauber with the protecting cap in place as in disuse.

Figure 2 is a partial central, vertical section showing the construction of the bristle tuft and the paste tube connections.

Figure 3 is a detail perspective view of the protecting cap, removed.

Figure 4 is a view similar to Figure 2, showing a modified form of my invention, and,

Figure 5 is a detail horizontal section taken therethrough, substantially on line 5—5 of Figure 4.

Referring now to these figures and especially

to Figures 1 and 2 which illustrate what I believe to be the best mode so far devised for carrying my invention into practise, I have shown the assembly as including a handle 10, a bristle tuft generally indicated at 11, and a fountain or paste tube 12. A protecting cap 13, also forms a part of this assembly, and as hereinafter more specifically referred to, may be used in connection with the bristle tuft in any of several structures otherwise modified with respect to one another.

In Figure 2 in particular, the fountain or paste tube 12, is shown with its discharge end 14, having an internally threaded orifice, and the bristle tuft 11, is shown as comprising bristles 15, for applying paste from the tube 12, to the work, whose confined ends are clamped around a tubular core member 16, by a cylindrical confining or body band 17.

The free ends of the bristles 15, project substantially beyond the respective end of the band 17, and the opposite end of this band projects a short distance beyond the confined ends of the bristles so as to form a cup-like cavity for the reception of the discharge end of the paste tube. The core member 16, has a reduced threaded extension 18, upstanding into the tube-receiving cavity of the bristle tuft, and this extension forms an anchor for the paste tube since it is adapted to screw into the internally threaded orifice of the tube, as shown in Figure 2, thus locking the discharge end of the tube in the cavity and firmly supporting the tube in axial alinement with the bristle tuft 11.

The core member 16, being tubular, permits the paste, squeezed as needed from the collapsible paste tube, to pass to the free or applying ends of the bristles 15.

The handle 10 may be generally flat, as shown, possibly with a flanged edge if stamped from sheet metal, and extends at right angles to the tube and bristle tuft. It is shown with an opening at one end to receive the body band 17 of the bristle tuft, and with a flange 19 surrounding its said opening in order that it may conveniently be secured to the said band by soldering, brazing or welding.

According to the modified structure shown in Figures 4 and 5, the bristle tuft 11a is generally similar to that of Figures 1 and 2, since the confined ends of the bristles 15a are clamped around a tubular core member 20 by a confining or body band 21. The upper ends of the core member 20 and band 21, however, terminate flush, or substantially flush, with the con-

fined ends of the bristles, the core member 20 is, moreover, internally threaded to receive the lower externally threaded end of a tubular feed member 22 whose upper end is internally 5 threaded and has an enlarged upwardly opening cup-like extension 23.

The handle 10a may be the same as that of Figures 1 and 2, except for the omission of the flange around its end opening, since in this 10 modified structure the feed member 22 passes through the handle opening so that when it is threadedly engaged with the core member 20, its enlarged extension 23 clamps the handle between the same and the adjacent end of the 15 bristle tuft 11a.

The fountain or paste tube 12a in the modified construction has an externally threaded discharge nipple 24 which is diametrically notched as at 25 in Figure 5, to extend through 20 the central opening of the disc 26 having inwardly projecting diametrical lugs 27 to inter-fit the notches 25. The disc 26 rotatably inter-fits the lower portion of the cup-like extension 23 of the feed member 22, and is confined there- 25 in by inwardly struck up ears 28 of the wall of this extension at opposite points. Thus, although snugly embracing the notched discharge nipple 24 of the paste tube, the disc 26, being freely rotatable, permits of readily screwing 30 the nipple 24 into and out of engagement with the upper internal threads of the feed member 22.

Thus each form of my invention as described 35 and shown makes it necessary to employ a specially prepared fountain or paste tube, and each provides for ready removal of an empty, collapsed tube, for the substitution of a full tube.

The problem remains, however, to protect the bristles against drying and hardening of the 40 paste left therein after each use thereof, and this problem I have solved by the employment of a tapering, hollow cap 13 shown applied in Figure 1, and in detail in Figure 3. The smaller end of the cap 13, which is closed, snugly confines the bristles and the larger open end thereof 45 telescopes the confining or body band of the bristle tuft. Ordinarily it is a difficult matter to properly feed the freely extending bristles into a protecting cap of this nature, but this 50 difficulty I have overcome by cutting away a portion of the upper edge of the cap as at 30 for slightly less than one-half its circumference. The terminal shoulders of the remainder of said edge, at opposite sides of the said cut 55

out portion are flared outwardly, as shown, in the form of curved guide ears 31.

Thus, by placing the free ends of the bristles into the upper open end of the cap 13, through the cut away portion thereof, and gradually 80 rotating the cup as it is pressed upwardly around the bristle tuft to telescope the body band, one of the ears 31, dependent upon the direction of such rotation, will gather in the stray bristles and completely and easily encompass them, without danger of bending or breaking the bristles. It is to be understood that, when applied, the cap is held in this position by frictional engagement with the body band 85 of the bristle tuft which it telescopes.

Furthermore, although I have outlined thus fully but two possible structural exemplifications of my invention, it is to be understood that it may be embodied in other and further forms, and that I expressly reserve all such as fall 90 within the terms of the following claims.

What I claim is:

1. A protecting cap for the bristles of shoe daubers, said cap having a closed end and having its opposite end open and partially cut away, 100 forming opposite shoulders, said shoulders being flared outwardly and forming bristle gathering ears.

2. A protecting cap for the bristles of paste daubers, said cap being open at one end and 105 having a cut away portion adjacent to said open end, and bristle gathering means at opposite sides of said cut away portion.

3. A fountain shoe dauber including a bristle tuft having an internally threaded tubular core 110 member, a tubular feed member threaded at one end into said core member and having internal threads and an enlarged extension at its opposite end, a paste supply tube having one end seated and housed within said extension and 115 having a threaded nipple engaging the internal threads of the feed member, and a disc through which the nipple extends, rotatably held in said extension, said disc and said nipple having registering notches and projections for the purpose 120 set forth.

4. A protecting cap for the bristles of paste daubers, said cap being of tubular form having one end closed and its other end open, the cap being cut away adjacent to its open end and 125 having bristle gathering ears formed at opposite sides of said cut away portion.
